DISPLAY TRAY

Richard F. Reifers, New Canaan, Conn., assignor to Diamond International Corporation, a corporation of Delaware

Filed Apr. 23, 1964, Ser. No. 79,673

Term of patent 14 years

(Cl. D58—13)

FIG. 1 is a top plan view of a display tray showing my new design;

FIG. 2 is an end elevation looking from right to left at FIG. 1, the side opposite being the same in appearance;

FIG. 3 is a side elevation looking into the lower portion of FIG. 1, the side opposite being the same in appearance;

FIG. 4 is an enlarged fragmentary cross-section on the plane of line 4—4 of FIG. 1;

FIG. 5 is an enlarged fragmentary elevational view looking from the plane of line 5—5 of FIG. 1 and showing a corner detail; and

FIG. 6 is a fragmentary perspective view looking into the upper left hand corner of the display tray.

The characteristic feature of the design resides in the upstanding, arcuate corner margins and their merging

relationship down to the relatively lower margin portions therebetween as illustrated in the elevational views.

I claim:

The ornamental design for a display tray, as shown and described.
